AIR BRAKE HOSE COUPLING OR SIMILAR ARTICLE

Richard R. Kozinski, Canton, Ohio

Application May 2, 1958, Serial No. 50,731

Term of patent 14 years

(Cl. D66—1)

FIG. 1

FIG. 2

FIG. 3

FIG. 4

Fig. 1 is a top plan view of an air brake hose coupling or similar article, embodying my new design, an identical article being shown in broken lines connected thereto for purpose of illustration only.

Fig. 2 is a front elevational view.

Fig. 3 is a bottom plan view.

Fig. 4 is a rear elevational view.

I claim:

The ornamental design for an air brake hose coupling or similar article, substantially as shown and described.
